UNITED STATES PATENT OFFICE.

GEORGE CHARLES GILLESPIE YOUNG AND MARTIN MAGILL WADDELL, OF BALLYMENA, IRELAND.

PROCESS OF SPINNING.

1,051,361.

Specification of Letters Patent.

Patented Jan. 21, 1913.

Application filed February 2, 1906. Serial No. 299,164.

To all whom it may concern:

Be it known that we, GEORGE CHARLES GILLESPIE YOUNG and MARTIN MAGILL WADDELL, British subjects, and residents both of 5 Ballymena, county Antrim, Ireland, have invented certain new and useful Improvements in Processes of Spinning, of which the following is a specification.

In the wet spinning of flax and kindred 10 fibers the rove is immersed in a trough of hot water and thoroughly saturated as it passes to the drawing rollers for the purpose of facilitating the action of drawing and the wet rove after being drawn to the desired 15 degree of fineness passes direct to the bobbin or purn and is twisted and wound upon the bobbin or purn in a wet state.

In the spinning of cotton, flax and other 20 fibers in a dry state the rove is drawn to the desired degree of fineness and passes direct 25 from the rollers to the bobbin or purn. We have found that a stronger and better yarn is produced by applying heat to and drying the untwisted rove after it has been drawn out to the desired degree by the drawing 30 action of the drawing rollers and before it is twisted into a finished yarn, the separate fibers being thereby rendered more cohesive and the drawn rove consequently strengthened thereby adding greater strength and 35 evenness to the finished yarn.

Our present invention consists in (a) drying 35 a wet untwisted rove after it leaves the front drawing rollers before receiving any twist; (b) winding the rove when dry after 40 drawing into a roll without twisting it; (c) twisting the dry rove into yarn by rotating it in the form of a roll at a rapid rate while the yarn is drawn off by a pair of rollers.

The invention will be fully described with reference to the accompanying drawings:—

Figure 1 is a transverse sectional elevation of apparatus employed for drying the rove A and winding it into a roll A'. Fig. 2 is a transverse section of modified construction of drying apparatus. Fig. 3 is a transverse sectional elevation of apparatus for twisting the rove A—from the 45 roll A'—into yarn and winding the yarn into a second roll A². Fig. 4 is a transverse section of modified construction of apparatus winding a dry rove into a roll A'. In wet spinning the rove A is passed 50 through hot or cold water in the trough C

and drawn between the drawing rollers B to the requisite degree of fineness in the usual way. The drawn rove A after it emerges from the nip of the drawing rollers B and before it is twisted is dried to a degree 60 sufficient to consolidate the wet fibers to a cohesive condition. The untwisted rove A as it passes from the nip of the drawing rollers B is delivered onto a traveling flannel or blanket D which absorbs and presses 65 out the moisture from the rove A. The flannel or blanket D passes in contact with hot cylinders D' and D² heated by steam or gas and over a number of guide rollers d.

The rove A may be pressed between the 70 blanket or flannel D and a second blanket or flannel D³ as in Fig. 1, or it may be carried by the blanket or flannel D into direct contact with the heated cylinder D' as in Fig. 2. Or the untwisted rove A may be 75 dried in any other way such as by passing directly over hot plates, pipes, rollers or cylinders.

The untwisted rove A when dried is passed 80 from the blanket or flannel D to a winding roller or drum E and is thereon wound into a roll A'.

In dry spinning when a dry yarn is being dealt with the untwisted dry rove is wound 85 into a roll without twist but to consolidate or give sufficient cohesion to the fibers there- 90 of to enable such to be handled it is passed through a condensing device or between reciprocat- 95 ing or vibrating rubbers D⁴ Fig. 4, after leaving the drawing rollers B. The condensing or rubbing device D⁴ gives sufficient coherence to the untwisted drawn rove and renders it strong enough to be wound up into the roll A' by the winding roller E.

The roll A, of consolidated dry or dried 95 untwisted rove is placed upon a spindle F and the rove drawn off therefrom by a pair of rollers G. The spindle F is rotated at a high velocity say 10,000, 50,000 or even 100,000 revolutions per minute thus giving 100 the desired amount of twist to the rove A' and converting it into yarn which is wound up as quickly as delivered into a roll A² by the winding roller E'. The spindle F and the roll of untwisted rove upon it is surrounded by or inclosed within a fixed or stationary shield H to prevent the loose end of the yarn ballooning or flying off at right angles to the spindle. The shield is at the top provided with a guide eye h through 110

2
which the rove is delivered to the roller G as it is drawn off from the roll A'.

- This method of spinning by winding the untwisted rove A into a roll A', and then twisting it into yarn by placing the roll A' onto a spindle which is rotated rapidly while the rove is being drawn off as shown in Fig. 3, may be applied to jute, cotton, wool or other fibers which are drawn and twisted in the dry state, in which case the water trough C and the drying apparatus shown in Fig. 1, is dispensed with and the condensing apparatus shown in Fig. 4 is employed. In this method of spinning and twisting no strain at all is put upon the yarn the centrifugal motion of the roll A' throwing the rove off as quickly as it can be drawn forward by the rollers F and wound up again after being twisted upon the roll A'.
20 What we claim as our invention and desire to protect by Letters Patent is:—
1. The method or process of wet spinning which consists in passing the rove through a trough of water to saturate the fibers with 25 water and drawing the fibers while so saturated into an untwisted rove of the desired

degree of fineness, for spun yarn, drying and consolidating the untwisted drawn rove before twisting and only imparting to it the desired degree of twist after being dried, 30 substantially as described.

2. The method or process of wet spinning which consists in passing the rove through a trough of water to saturate the rove with water and drawing the fibers while so saturated into an untwisted rove of the ultimate degree of fineness for spun yarn, drying and consolidating the untwisted drawn rove, winding the dried consolidated drawn rove onto a spool without twist withdrawing the 40 same from the spool and subsequently imparting to it while still dry the desired degree of twist substantially as described.

In witness whereof, we have hereunto signed our names in the presence of two sub- 45 scribing witnesses.

GEORGE CHARLES GILLESPIE YOUNG.
MARTIN MAGILL WADDELL.
